(57) **CLAIM**

The ornamental design for a latch and associated mounting hardware for combine concaves, as shown and described.

DESCRIPTION

FIG. 1 is a perspective view of a first embodiment for a latch and associated mounting hardware for combine concaves; FIG. 2 is another perspective view thereof; FIG. 3 is a front elevation view thereof, the back elevation view being a mirror image thereof; FIG. 4 is a top plan view thereof; FIG. 5 is a bottom plan view thereof; FIG. 6 is a left elevation view thereof; FIG. 7 is a right elevation view thereof; FIG. 8 is a first reference perspective view thereof; FIG. 9 is another first reference perspective view thereof; FIG. 10 is a first reference front elevation view thereof, the first reference back elevation view being a mirror image thereof; FIG. 11 is a first reference top plan view thereof; FIG. 12 is a first reference bottom plan view thereof; FIG. 13 is a first reference left elevation view thereof; FIG. 14 is a first reference right elevation view thereof; FIG. 15 is a second reference perspective view thereof; FIG. 16 is another second perspective view thereof; FIG. 17 is a second reference front elevation view thereof, the second reference back elevation view being a mirror image thereof; FIG. 18 is a second reference top plan view thereof; FIG. 19 is a second reference bottom plan view thereof; FIG. 20 is a second reference left elevation view thereof; and FIG. 21 is a second reference right elevation view thereof. FIG. 22 is a perspective view of a second embodiment for a latch and associated mounting hardware for combine concaves; FIG. 23 is another perspective view thereof; FIG. 24 is a front elevation view thereof, the back elevation view being a mirror image thereof; FIG. 25 is a top plan view thereof;

(Continued)

FIG. 26 is a bottom plan view thereof;
 FIG. 27 is a left elevation view thereof; and,
 FIG. 28 is a right elevation view thereof.
 Environment shown in dash-dash broken lines forms no part
 of the claimed design.
